UNITED STATES PATENT OFFICE.

LOUIS A. CASGRAIN, OF BEVERLY, MASSACHUSETTS.

ENGINE-PRIMER.

1,281,291.

Specification of Letters Patent. Patented Oct. 15, 1918.

Application filed March 8, 1917. Serial No. 153,375.

To all whom it may concern:

Be it known that I, LOUIS A. CASGRAIN, a citizen of the United States, residing at Beverly, in the county of Essex and State 5 of Massachusetts, have invented certain new and useful Improvements in Engine-Primers; and I do hereby declare the following to be a full, clear, and exact description of the invention, such as will enable others 10 skilled in the art to which it appertains to make and use the same.

The present invention relates to priming devices for internal combustion motors, and more particularly to priming devices of this 15 character adapted for attachment to existing motors having the usual form of carburetor.

It is desirable, especially in cold weather, to have some sort of auxiliary device which 20 may be actuated to inject a small quantity of liquid fuel directly into the intake manifold between the carburetor and the motor. A device of this character is especially necessary in connection with the low grade 25 fuels at present in use as it enables the employment of a more volatile liquid fuel for priming purposes.

An object of the present invention is to 30 provide a priming device of a simple and compact construction which may be readily attached to existing types of motors, and which enables a small quantity of liquid to be injected into the intake manifold.

A further object of the invention is to 35 provide a single unitary apparatus which may be conveniently controlled by the operator for injecting either liquid fuel or air or both into the intake manifold when desired.

40 With these objects in view the several features of the invention consist in certain novel features of construction, combination and arrangement of parts hereinafter described and claimed, the advantages of 45 which will be obvious to those skilled in the art from the following description.

In the accompanying drawings illustrating the preferred form of the invention Figure 1 represents an elevation of the preferred priming device ready for attachment; Fig. 2 is a longitudinal section in elevation of the device shown in Fig. 1; Fig. 50 3 is a detail showing a section of the valves and actuating devices controlling the flow 55 of liquid and air into the intake manifold;

and Fig. 4 is a detail showing the means for operating the valve.

In the illustrated embodiment of the invention the apparatus comprises a fuel receptacle indicated at 5 having a discharge pipe 6 leading from the bottom and adapted to be connected in any suitable manner with the usual intake manifold of the motor. The apparatus is also provided with an air pipe 7 communicating with the discharge pipe 6 through suitable passages and valves to be hereinafter described, thus permitting both air and liquid to be injected into the intake manifold.

The receptacle 5 consists of a thin metallic shell 8 which is mounted upon and secured to a base 10 having an extended tubular portion 11 received within a supporting ring 12 as shown clearly in Fig. 2. Fitting within the tubular portion 11 of the base is a tube 14, formed of brass or similar material which is not affected by the gasoline. The upper end of this tube extends above the base 10 and is provided with one or more openings 15 to permit the flow of gasoline from the receptacle 5 through the tube into the discharge pipe. The flow of gasoline from the receptacle into the discharge pipe is controlled by a plunger 16 sliding within the tube 14 and actuated by a rod 17 extending completely through the receptacle, and guided at the top in a bearing 18 secured in the top portion of the shell 8. In order to prevent the escape of fumes from the gasoline, or other liquid fuel contained within the receptacle, the bearing for the plunger rod is packed with flexible material indicated at 19. This flexible packing is kept tight by a disk 22 pressed against it through a spring to be hereinafter described. In order to prevent the escape of liquid into the discharge pipe when the plunger is in a depressed position the tube 14 is provided with a conical bottom 20 having an opening 21 formed in the apex which is adapted to be closed by a needle valve 23 depending from the lower end of the plunger 16, as shown clearly in Fig. 2. The needle valve 23 is connected to the plunger through a fulcrum pin 24 permitting the needle valve to be centered with relation to the opening when the plunger descends.

Owing to the formation of the bottom of the tube 14 and the hinged connection between the needle valve and plunger, the end 105 110

of the needle valve is caused to engage with and close the opening when the plunger descends. The plunger is raised to elevate the lower end above the opening 15 by a 5 knob 26 secured to the upper end of the plunger rod and is returned to initial position to close the opening 21 by a spring 27 surrounding the plunger rod and interposed between the plunger and the disk 22. In 10 order to prevent the complete withdrawal of the plunger from the tube 14, the spring 27 is so designed that when the lower end of the plunger reaches a position above the opening 15 the coils of the spring will contact with one another, preventing further upward movement of the plunger. The filling of the receptacle 5 is conveniently accomplished through an opening closed by a removable cap 28 normally held in place by a 15 spring 29. The cap 28 is conveniently retained in position to leave the opening exposed by a hook 34 arranged to engage over the edge of the shelf when the cap is withdrawn from the opening.

25 It is very desirable that a single unitary apparatus be provided for both the injection of liquid and air into the intake manifold. To this end the present construction includes an air valve with coöperating devices 30 for controlling the flow of air into the manifold. The air pipe 7 is threaded at its inner end in the ring 12, which is provided with an air passage 30 adapted to communicate with the discharge pipe 6 through an air 35 opening 31 leading into the discharge pipe below the bottom of the tube 14. The flow of air through this opening is controlled by a rotatable sleeve 32 having an opening 33 formed therein which is adapted to register 40 to a greater or less extent with the opening 31. The sleeve 32 is actuated by a laterally extending handle 35, the movements of which are limited by a pin 37 secured in the ring 12 and projecting into an arcuate slot 45 38 formed in the upper face of the sleeve, as shown clearly in Fig. 4 of the drawings. The sleeve is journaled upon the tubular extension 11 of the base and is retained in place by a locking nut 40. This construction 50 permits the injection of air into the manifold both in combination with the liquid fuel and independently of the liquid when it is desired to secure a lean mixture.

The apparatus is conveniently adapted 55 for attachment to the dash of an automobile and to this end a bracket 41 is clamped to the base ring through the air pipe 7. In the illustrated embodiment of the invention the bracket 41 is provided with an annular 60 shoulder 43 which is engaged by a clamp disk 44 held in place against the shoulder by a lock nut 45 threaded upon the pipe 7. The bracket 41 is provided with oppositely 65 extending feet 46 which are adapted for the reception of fastening members to enable

the priming device as a whole to be supported upon the dash. In the illustrated embodiment of the invention the air pipe is made of sufficient length to extend completely through the dash drawing air from 70 beneath the hood, and the outer end of the air pipe is threaded for the reception of a nut to cause the air pipe to act as an additional securing means.

It will be observed that with the priming 75 device located in this manner upon the dash, it is conveniently accessible to the operator both for the priming of the motor preparatory to starting and for regulating the amount of air injected into the motor during 80 the operation. The laterally extending handle 35 may be conveniently turned by the foot or hand of the operator, regulating the injection of air into the manifold as desired. Furthermore, the provision of the 85 small orifice 21, in connection with the air opening, causes the gasoline or other liquid which is injected into the manifold to be thoroughly broken up and atomized.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. A priming device, having in combination, a liquid receptacle, a discharge pipe leading therefrom and adapted to be connected with the intake manifold of a motor, a tube projecting into the lower portion of the interior of the receptacle and having 100 openings at the top portion leading into the liquid receptacle at a predetermined height above the bottom and a restricted opening at the bottom leading to the discharge pipe, a plunger sliding within the tube, a valve 105 carried by the plunger and adapted to close the opening when the plunger is located at the bottom of the tube, and a spring for normally maintaining the plunger at the bottom of the tube to permit liquid to flow 110 from the receptacle into the tube when the plunger is elevated and to be thereafter ejected by the plunger when the latter is released and returned by the spring to cause a substantially measured amount of liquid to 115 be delivered to the discharge pipe.

2. A priming device, having in combination, a liquid receptacle having a tubular extension projecting downwardly therefrom, and having a restricted opening in the bottom, a supporting ring for the receptacle surrounding the extension and having an air passage formed therein, a discharge pipe connected with the ring, an air intake pipe secured to the ring and communicating with 120

the air passage formed therein, a sleeve valve journaled in the extension and controlling the passage of air from the intake pipe to the discharge pipe, and a plunger received 5 in the tubular extension and adapted to forcibly eject liquid through the opening when the plunger descends into the tubular extension.

3. A priming device comprising a liquid 10 receptacle, a tubular extension extending from the bottom of the receptacle, a tube of noncorrodible material fitting within the extension, a plunger slidingly supported within the tube, a stem secured to the plunger and extending completely through the 15 receptacle, a bearing for the stem mounted upon the top of the receptacle and having a

flexible packing supported therein, a disk 20 engaging with the packing, and a spring surrounding the stem and interposed between the plunger and disk for normally retaining the plunger in depressed position and for pressing the disk against the packing.

4. A priming device comprising a liquid 25 receptacle, a supporting ring for the receptacle, a discharge pipe, connections between the receptacle and discharge pipe, an air intake pipe secured to the ring, a bracket for attaching the device to a motor vehicle, and 30 means mounted upon the intake pipe for securing the bracket to the supporting ring.

LOUIS A. CASGRAIN.
